UNITED STATES PATENT OFFICE.

WALTER L. BOARDMAN, OF DECATUR, ILLINOIS.

WAGON-BRAKE.

SPECIFICATION forming part of Letters Patent No. 606,403, dated June 28, 1898.

Application filed January 17, 1898. Serial No. 666,918. (No model.)

To all whom it may concern:

Be it known that I, WALTER L. BOARDMAN, of Decatur, in the county of Macon and State of Illinois, have invented a certain new and 5 useful Combined Brake-Lever, Ratchet-Rack, and Whip-Socket for Wagons, of which the following is a specification.

The invention relates to certain details of construction whereby various advantages are 10 obtained. It is exemplified in the structure hereinafter described and it is defined in the appended claims.

In the drawings forming part of this specification, Figure 1 is a side elevation of the 15 front end of a side of a wagon-bed with my invention attached thereto. Fig. 2 is an elevation of the inner surface of the ratchet-rack. Fig. 3 is an elevation of the outer surface of the combined whip-socket and pivot- 20 arm for the brake-lever. Fig. 4 is an edge elevation of the brake-lever. Fig. 5 is a vertical section through the whip-socket. Fig. 6 is a plan of a yielding ring contained in a groove in the whip-socket.

25 The whip-socket 1 is approximately semi-cylindrical in cross-section, it is open from end to end, a portion of its convex or outer surface is cut away, as shown at 5, and one of the side walls so exposed is built outward 30 to form a rib 4. The arm 2, on which the brake-lever is pivoted, is cast integral with the whip-socket. It extends obliquely downward and backward from the lower end of the socket, and it has at its end a perforated 35 boss 3, which acts as a pivot-bearing for the brake-lever. The ratchet-rack 7 is arched, toothed on its under surface, has a vertical groove 9, adapted to fit over the rib 4 of the whip-socket, and its ends are perforated, as shown at 10 and 11. The brake-lever 14 is pivoted on the boss 3 of arm 2 and extends upward therefrom adjacent to the 40 ratchet-rack. It is provided with a pawl 15, which is adapted to engage the teeth of the rack and which has a weighted end 16. The 45 weighted end 16 acts to force the pawl into contact with the rack, and it may be forced into contact with the teeth, as shown in broken lines in Fig. 1. A grip-lever 17 is pivoted on the upper end of the brake-lever, and a rod 50 18 connects the grip-lever with the weighted end of the pawl. A strap 19 (shown in Fig.

4) is fastened to the brake-lever above the rack and below the pawl, and it extends inward around the rack and the pawl in a manner to embrace the rack somewhat loosely and to support an end of the pivot-pin of the pawl.

55 The whip-socket is preferably grooved internally, as shown at 6, and provided in such groove with a yielding ring 20, of rubber or the like, which ring has an external shape approximating that shown in Fig. 6. It is the purpose of the yielding ring to aid in retaining the whip firmly in the socket.

65 The rack, the whip-socket, and the pivot-arm are secured to the side of the bed by bolts 12, 13, and 21. The rack fits against the whip-socket, with its groove 9 fitting the rib 4, which compels the rack to assume a position concentric with the hole in boss 3 of arm 2, and the bolt 12 aids in holding both the rack and the whip-socket in position. The bolt has a further function—namely, to form the bottom of the whip-socket, and it does 70 this in a manner to support the whip effectively, while permitting dirt and the like to pass through. The bolt extends through the center of the opening through the socket, and there is plenty of space on the sides of the 75 bolt for passage of dirt. The bolt 13 holds the extended end of the rack in position, and the bolt 21 aids in holding arm 2 in position and acts as a pivot for the brake-lever.

80 The brake-lever is outside the rack, where it cannot rub against the bed, and it is held in operative position by strap 19.

85 The pawl is counterbalanced to engage the rack by force of gravity, and the counterbalanced end may be used to prevent extreme jar on the arm of the operator. To effect this result, the grip-lever is pressed sufficiently hard to disengage the pawl and force the rounded surface 16 against the teeth, and the pressure may be regulated so as to develop just enough friction to permit the lever to move slowly backward and relieve the 90 brake.

95 The lever is connected from hole 22 with the brake mechanism of the wagon, and such mechanism may be of any desired construction.

What I claim is—

1. In a wagon-brake, the combination of a

vertical whip-socket open from end to end and having an integral pivot-arm extending downward and backward, a ratchet-rack fastened at one end to the whip-socket by a bolt 5 which extends through the socket and forms a support for the whip, such rack being extended in an arc concentric with the end of the pivot-arm and a brake-lever pivoted on the end of the arm, substantially as set forth.

10 2. In a wagon-brake, the combination of the rack having teeth in its under surface, the

brake-lever pivoted concentric with the rack, the pawl on the lever having the engaging end 15 and the rounded counterbalancing end 16 adapted to bear frictionally against the 15 teeth, substantially as set forth.

In testimony whereof I sign my name in the presence of two subscribing witnesses.

WALTER L. BOARDMAN.
